UNITED STATES PATENT OFFICE.

CHARLES E. MCLEAN, OF POWERSVILLE, MISSOURI.

DEVICE FOR LOADING WAGONS.

SPECIFICATION forming part of Letters Patent No. 514,543, dated August 13, 1895.

Application filed September 20, 1894. Serial No. 523,631. (No model.)

To all whom it may concern:

Be it known that I, CHARLES E. MCLEAN, a citizen of the United States, and a resident of Powersville, in the county of Putnam and State of Missouri, have invented certain new and useful Improvements in Devices for Loading Wagons; and I do hereby declare that the following is a full, clear, and exact description of the invention, which will enable others

skilled in the art to which it appertains to make and use the same, reference being had to the accompanying drawings, which form a part of this specification, and in which—

Figure 1 is a perspective view of my apparatus or device for loading wagons, showing the same as it appears when in use, but with the team unhitched from the loading-shovel; and Fig. 2 is a side elevation of the same with some of the parts shown in section.

Like letters of reference designate corresponding parts in both the figures.

This invention has relation to means for loading wagons with earth or gravel, manure, sand, and similar material which is loaded "in bulk" and in large quantities at a time; and it consists in the construction and combination, with a wagon, of two inclined planes or platforms, which are used in combination with a sliding loading-shovel and connected to the wagon to be loaded at opposite ends of the same, substantially as will be herein-after more fully described, and particularly pointed out in the claims.

On the accompanying drawings, the reference-letter A denotes the wagon which is to be loaded, for example, with manure. After this has been driven up to the point or place where it is to receive its load the team is unhitched, and an inclined plane or platform B, consisting of two or more parallel planks b b, with a narrow opening a between them, and connected to each other by cleats or cross-pieces c c on the under side, is hooked upon the headboard of the wagon-box by means of hooks C C at one end, while its other or lower end where it rests upon the ground is provided with prongs D D, which by entering the ground will prevent the platform B from slipping. Thus it will be seen that by means of the hooks C C at one end and pointed teeth or prongs D D at the other end the platform B is easily and firmly maintained in its in-

clined position between the headboard of the wagon-box and the ground. As this inclined plane or platform B is used only for sliding the empty loading-shovel down from the wagon-box after its load has been deposited in the box, it has no great weight to sustain and does not, therefore, require to be braced or supported between its upper and lower ends.

Another inclined platform E, also composed of two or more parallel planks e e, with an open space f between them and connected to each other by a series of transverse cleats or cross-pieces g g on the under side, is supported permanently upon a framework or scaffolding G, one end of which is provided with casters H H and also with hinged rods I I, (one on each side,) which are bent at their outer ends to form hooks i i. The inclined platform E extends beyond its supporting-frame G at both ends and is provided at its lowermost end with an anchor-plate J, having an aperture j, for the insertion of the anchor-pin K. The other end of the inclined plane E is elevated by means of the supporting-frame G to such a height that its upper end will slightly overlap the tailboard or end-gate of the wagon-box, and after the platform has (by means of the casters H H) been rolled up against the tail end of the wagon it is connected therewith by means of the hooked rods I I, the hooks i i of which are hooked over the felloes of the hind wheels, so that in connection with the anchor-pin K at the other end this platform E will also be firmly maintained in its inclined position at and impinging against the tail end of the wagon, as illustrated in the drawings. The loading-shovel L is in the nature of an ordinary road-scraper, preferably made of sheet metal and provided at its rear end with a pair of handles l l. By means of the bail M it is connected to a doubletree N of such length that the singletrees n n will swing clear of the two inclined platforms B and E and of the wagon A between them during the operation of loading the wagon.

From the foregoing description, taken in connection with the drawings, the manner of using this loading attachment or device will readily be understood. The wagon having been backed up close to the manure-heap, (or

gravel bank, as the case may be,) the team is unhitched and hitched to the singletrees *n n* of the loading-shovel L. Next the two platforms B and E are unloaded and connected 5 to the wagon-box at the opposite ends of the same, as hereinbefore described and shown on the drawings, care being taken to force the prongs D D appertaining to platform B firmly into the ground and also to drive the 10 anchor-pin K into the ground through the aperture in the anchor-plate J at the lower end of the loading-platform E. By finally hooking the side rods I I over the fellies of the hind wheels both the inclined platforms 15 B and E will be in position ready for use.

To load the wagon the loading-shovel L is first driven into the manure-heap until it is full, and is then, with its load, pulled up the inclined loading-platform E, the team going 20 on opposite sides of the platform and wagon, while the man in charge walks up the platform behind the shovel and guides it in its ascent by means of the handles *l l*. When 25 the top of the platform is reached, he lifts the handles and dumps the load into the bottom of the wagon, when the movement of the team will draw the shovel over onto the platform B. After reaching the ground the shovel is again pulled up to the place where it is to be loaded, 30 filled, and again pulled up the inclined platform E and dropped into the wagon, and this operation is repeated until the wagon is full.

In practice it will be found convenient and expedient not to dump the loading-shovel and 35 relieve it of its load until near the headboard, so as to deliver the load up against this, as

shown on Fig. 1, because this facilitates the carrying of the empty shovel up over the headboard by sliding it over the load or loads already deposited in the wagon upon the 40 raised end of platform B.

Having thus described my invention, I claim and desire to secure by Letters Patent of the United States—

1. The combination, with a wagon A, of the 45 triangular frame G, the hooked rods pivotally connected therewith, the casters at the inner end thereof, the inclined platform supported by said frame provided at its lower end with an apertured anchor plate and an anchor pin, the loading shovel provided with handles, and the doubletree connected with said shovel and projecting laterally beyond the sides of the platform and wagon, substantially as described. 50

2. In combination with the wagon A the inclined platforms E and B, connected removably to the wagon at opposite ends thereof, the loading-shovel L, provided with the handles *l l*, and doubletree M of such a length 60 that it will straddle both the inclined platform and the intermediate wagon-box; substantially as and for the purpose shown and set forth.

In testimony that I claim the foregoing as 65 my own I have hereunto affixed my signature in presence of two witnesses.

CHARLES E. MCLEAN.
